UNITED STATES PATENT OFFICE.

JOHN C. DUEBER, OF CANTON, OHIO.

DESIGN FOR A WATCH-CASE.

SPECIFICATION forming part of Design No. 21,549, dated May 17, 1892.

Application filed March 21, 1892. Serial No. 425,862. Term of patent 14 years.

To all whom it may concern:

Be it known that I, JOHN C. DUEBER, a citizen of the United States, and a resident of Canton, county of Stark, State of Ohio, have invented a new Design for Watch-Cases, of which the following is a full, clear, and exact description, reference being had to the accompanying drawings, making part of this specification.

Figure 1 is a perspective view of a watch-case; and Fig. 2 is an edge view of the same, partly in section.

The leading features of my design are the circular portion at the center of each lid, from which radiate oval ribs, which increase in breadth and are rounded at their edges, the

sharply-curved bezel portion having parallel oval or melon-shaped ribs, and the plain oval rim.

A is the circular portion; C, the radiating oval ribs; D, the ribbed bezel, and F the plain oval rim.

What I claim is—

The design for a watch-case, herein shown and described.

In testimony whereof I have hereunto set my hand this 15th day of March, A. D. 1892.

JOHN C. DUEBER.

Witnesses:

W. K. MILLER,
CHAS. R. MILLER.
